UNITED STATES PATENT OFFICE.

GAINS L. MERRELL, OF SYRACUSE, NEW YORK.

CHAIN-WHEEL CASING.

SPECIFICATION forming part of Letters Patent No. 414,774, dated November 12, 1889.

Application filed June 22, 1889. Serial No. 315,254. (No model.)

To all whom it may concern:

Be it known that I, GAINS L. MERRELL, a citizen of the United States, residing at the city of Syracuse, in the county of Onondaga and State of New York, have invented a new and useful Improvement in Chain-Wheel Casings, of which the following is a specification.

This invention relates to a chain-wheel casing in which guides are employed for guiding the entering portion of the chain upon the sprocket-wheel and stripping the retreating portion of the chain from the sprocket-wheel, thereby insuring the proper engagement of the chain with the wheel and its disengagement therefrom.

The invention consists of the improvements which will be hereinafter fully described, and pointed out in the claims.

In the accompanying drawings, Figure 1 represents a hoisting-tackle provided with my improved chain-wheel casing. Fig. 2 is a perspective view of the casing with the front guides removed. Fig. 3 is a similar view of the front guides. Fig. 4 is a vertical section in line $x-x$, Fig. 1. Fig. 5 is a bottom plan view of the casing.

Like letters of reference refer to like parts in the several figures.

A represents a sprocket-wheel, which is secured to the end of a shaft a , journaled in a hanger b . The latter depends from a traveling carriage B , mounted upon the track c .

D represents the rear plate of the wheel-casing, provided at its lower end with a lug d and with a hub or perforated boss d' , in which the shaft a revolves. The wheel A rests with its rear side against the boss d' .

E represents the front plate arranged in front of the wheel A and connected with the rear plate by rearwardly-projecting arms $e-e$, which engage against opposite sides of the lug d and are secured thereto by a bolt f . The rear plate D is provided along its upright edges with forwardly-projecting flanges $g-g$, which serve as external chain-guides. These guides are arranged adjacent to the outer sides of the entering and retreating portions of the chain, and are preferably made parallel with each other and connected at their upper ends by an arch-shaped flange g' , which is arranged nearly concentric with the chain-wheel. The lower ends of the outer guides

$g-g$ are slightly curved outwardly, so as to facilitate the entrance of the chain. The outer guides $g-g$, in conjunction with the connecting-arch and the rear plate, also serve as a case or hood to protect the sprocket-wheel and chain. The rear plate is provided on its inner side with two stripping guides $h-h$, which are arranged parallel with the outer guides on opposite sides of the boss d' . The outer or stripping surface of each of these ribs begins inside of the pitch-line of the sprocket-wheel at the upper end of each guide and extends downward in a tangential line, so that when the chain in engaging against the outer surface of one of these guides will be gradually stripped from the sprockets of the wheel in passing out of the wheel-casing. The ends of these inner rear guides are curved to facilitate the engagement of the chain with the outer surfaces thereof.

The front plate E is provided with two arms $i-i$, which are arranged parallel with the inner rear guides $h-h$, and project upwardly on both sides of the wheel-hub, so as to operate as inner stripping-guides on the front side of the wheel, while the ribs $h-h$ operate as inner stripping-guides on the rear side of the wheel. The wheel-casing is mounted on the shaft and held thereon between the hanger and sprocket-wheel against longitudinal movement.

The upper end of the rear plate D is provided with a socket-plate, which engages against opposite sides of the hanger by means of lugs $k-k$, and thereby secures the pulley-casing against lateral displacement.

In new drive-chains the joints are sometimes very stiff and apt to ride over and rest on the sprockets of the wheel, which frequently causes them to be broken. The chain in approaching the sprocket-wheel is guided toward the same and caused to firmly engage therewith by one of the outer guides g , thereby avoiding the liability of breaking.

When a chain and sprocket-wheel are employed for very heavy work, the links bind over the teeth of the sprocket-wheel in making its passage around the wheel, and have a tendency to cling to the wheel on the retreating side of the chain. This is avoided by the rear stripper-guides h and front stripper-guides i , arranged tangentially on the inside

of the chain, which liberate the chain from the wheel, and consequently allow the latter to work with more freedom. The innerstripper-guides are arranged within the outer guides, whereby channels are formed between the outer and inner guides, through which the chain moves toward and from the wheel, and whereby the chain is securely guided in its movements.

10 It is obvious that the front plate and its stripping-arms *i i* might be dispensed with; but this is not desirable, as it would cause the chain to wear unequally, owing to the stripper acting only on one side of the chain.

15 When the chain and wheel travel continually in one direction, only one of the outer guides *g* and one set of strippers are in operation, and the others could be dispensed with; but where the chain is intermittently reversed, 20 as is usual in hoisting-tackles, it is desirable to have both outer guides and both sets of strippers, as shown.

I claim as my invention—

1. The combination, with the chain-wheel, 25 of a casing provided with outer chain-guides arranged outside the periphery of the wheel, and inner stripper-guides arranged within the outer guides and projecting with their inner ends within the periphery of the wheel, 30 whereby channels are formed between the outer and inner guides, through which the

chain moves toward and from the wheel, substantially as set forth.

2. The combination, with the chain-wheel, 35 of a casing provided with outer chain-guides arranged outside of the periphery of the wheel, and inner stripper-guides projecting with their inner ends within the periphery of the wheel and composed of rear guides and front guides separated by a space through 40 which the chain-wheel moves, substantially as set forth.

3. The combination, with the rear plate *D*, 45 having outer guide-flanges *gg*, inner stripper-guides *h h*, and a lug *d*, of a front plate *E*, provided with inner stripper-guides *i i*, and arms *e e*, which engage against the lug *d*, and a fastening-bolt, substantially as set forth.

4. The combination, with the hanger, the 50 shaft journaled therein, and the sprocket-wheel secured to the shaft, of the wheel-casing arranged on the shaft between the wheel and the hanger and provided with lugs which embrace the sides of the hanger, substantially as set forth.

Witness my hand this 13th day of June, 1889.

GAINS L. MERRELL.

Witnesses:

THEO. L. POPP,

CARL F. GEYER.

It is hereby certified that the name of the patentee in Letters Patent No. 414,774, granted November 12, 1889, for an improvement in "Chain-Wheel Casings," was erroneously written and printed "Gains L. Merrell," whereas said name should have been written and printed *Gaius L. Merrell*; and that said Letters Patent should be read with this correction therein that the same may conform to the record of the case in the Patent Office.

Signed, countersigned, and sealed this 10th day of December, A. D. 1889.

[SEAL.]

CYRUS BUSSEY,

Assistant Secretary of the Interior.

Countersigned:

C. E. MITCHELL,

Commissioner of Patents.
